(57) **CLAIM**

The ornamental design for a hybrid aircraft with foldable tail and wings as shown and described.

DESCRIPTION

FIG. 1 is a front view of a hybrid aircraft with foldable tail and wings in a retracted configuration according to our new design;

FIG. 2 is a top view thereof in the retracted configuration;

FIG. 3 is a rear view thereof in the retracted configuration thereof;

FIG. 4 is a left view thereof in the retracted configuration thereof;

FIG. 5 is a right view thereof in the retracted configuration thereof;

FIG. 6 is a bottom view thereof in the retracted configuration thereof;

FIG. 7 is a front-top-left perspective view thereof in the retracted configuration thereof;

FIG. 8 is a rear-top-left perspective view thereof in the retracted configuration thereof;

FIG. 9 is a front view thereof of the hybrid aircraft with foldable tail and wings in an extended configuration according to our new design;

FIG. 10 is a top view thereof in the extended configuration;

FIG. 11 is a rear view thereof in the extended configuration thereof;

FIG. 12 is a left view thereof in the extended configuration thereof;

FIG. 13 is a right view thereof in the extended configuration thereof;

FIG. 14 is a bottom view thereof in the extended configuration thereof;

FIG. 15 is a front-top-left perspective view thereof in the extended configuration thereof; and,

FIG. 16 is a rear-top-left perspective view thereof in the extended configuration thereof.

The dashed lines show portions of the hybrid aircraft with foldable tail and wings that form no part of the claimed design.
